UNITED STATES PATENT OFFICE.

CHARLES M. SZIRMAJ, OF NEW YORK, N. Y.

SAFETY RAZOR.

Application filed March 7, 1923. Serial No. 623,426.

To all whom it may concern:

Be it known that I, CHARLES M. SZIRMAJ, a citizen of the United States, residing at New York city, borough of Manhattan, in the county of New York and State of New York, have invented certain new and useful Improvements in Safety Razors, of which the following is a specification.

This invention relates to safety razors and has particular reference to that construction of razor which includes an adjustable blade or one whose edge is variable with respect to the guard means and especially to the means for attachment made effective easily and readily by the hand that holds the razor handle.

Another object of the invention is to improve the construction with respect to the relation between the blade edge and its guard means so as to afford perfect freedom or clearance for the passage of the shavings, or in other words, a construction in which the guard means is a smooth bar extending continuously in a certain line spaced from 25 and parallel to the edge of the blade.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a side elevation of a safety razor, parts being in section on the line 1—1 of Fig. 3.

Fig. 2 is a longitudinal section on the line 2—2 of Fig. 1.

Fig. 3 is a horizontal section on the line 3—3 of Fig. 1, indicating the head and adjacent parts in bottom plan.

Referring now more specifically to the drawings I show my improved razor as comprising a relatively small number of parts including a handle 10, the upper end 11 of which at least is hollow or tubular.

12 is a head comprising primarily a substantially flat plate portion having on its lower or under side a hub 13 directed toward the handle and externally screw threaded. 55 Adjacent to the side edges of the head are formed or suitably secured a pair of straight

smooth guard bars 14 each connected to the main portion of the head by curved arms 15. The effective edges of the bars are thereby upturned so as to extend longitudinally along and lie in a plane parallel to but above the plane of the main portion of the head. The head is formed at its center with a hole 16 passing directly through the center of the hub 13, and on opposite sides of this hole are two other smooth holes 17.

Any suitable means may be provided to secure the handle rigidly to the head though preferably for the purpose of thorough cleansing of the parts the head and handle are connected detachably, as by means of a yoke comprising a thimble 18 and a pair of spaced straps 19 and whereby the yoke may be termed skeletonized. The thimble is shown internally threaded for direct co-operation with the hub and to abut against the under surface of the head. It will be understood that in practice the connection is tight between the handle and the head and these parts if desired may be retained so connected more or less permanently.

Along the upper side of the head is formed a relatively narrow longitudinal ridge 20 which extends beyond the plane of the guide bars above referred to and remote from the main plane of the head. The holes 16 and 17 are formed also through this ridge. The spaces on opposite sides of the ridge, between the ridge and said upturned lateral edges, constitute channels to receive and hold shavings during the process of shaving.

Any suitable type of blade may be used in connection with this razor, but preferably one of the well known flexible species having two sharp edges is used as shown at 21. This type of blade ordinarily is formed with a row of three centrally arranged holes for attachment purposes and which register with the holes in the head above referred to. This blade is applied next to the ridge.

An outer plate 22 is applied next to the blade remote from the head and is preferably of crescent or concavo-convex form in cross section, the concavity being next to the blade. The plate 22 has a central threaded shank 23 fixed thereto and projecting downward through the center of the blade and head and slightly beyond the hub 13. The plate has also two studs 24 to pass through the other holes of the blade and head to hold the parts from relative rotation in a

well known manner. The blade is preferably of flat type but adapted to be flexed during the clamping and adjusting thereof for practical use. When the threaded shank 23 is drawn downward toward the handle the parallel edges of the plate 22 bearing downward upon the side portions of the blade cause the bending of the blade downward below the plane of the top of the ridge and toward the plane of the bars 14. It is even possible to so adjust the edges of the blade as to cause them to come within the plane of the bar edges, though in this limit of adjustment the cutting edges of the blade will have lost their efficacy. For practical use the adjustment approximates that shown best in Fig. 2 in which the edges of the blade are slightly above the plane of the guide bars.

20 The best means now known to me for effecting the adjustment of the plate 22 and blade consists of a cylindrical nut 25 located within the yoke and having adjacent to its lower end an annular groove 26 into which the portion 11 of the handle may be spun, making a permanent connection between the nut and handle but with freedom of rotation of the nut within the handle and yoke. The upper end of the nut lies adjacent to the hub, more or less closely, and is provided with a threaded bore 27 for direct co-operation with the threaded shank 23. The reaction between the nut and the shank may take place either against the hub at the end of the nut or between the grooved end of the nut and the handle, but in either event the shank and plate 22 are drawn downward toward the head, causing the flexing transversely of the blade. The nut is easily accessible for rotation between the thumb and first finger of either hand of the operator, as for instance, the hand that grasps the handle in his last three fingers, and yet in the practice of the razor the manipulation is had only with the handle and no danger of misadjustment by the accidental turning of the nut takes place.

It will be noted that there is considerable space or capacity for the hairs and lather to be received between the blade and the main portion of the head, but the shavings

may pass freely through the slots 28 formed between the bars 14 and the main portion of the head, so that there can be no possibility of clogging of the instrument while in use. Furthermore these large clearances or spaces insure easy and thorough cleansing or rinsing of the shavings therefrom while the shaving operation progresses. After the operation is over the blade is easily removed for cleansing and drying by simply spinning the nut and thereby causing the plate 22 to move upward from the head, thus setting the plate and blade free.

I claim:

1. In a safety razor, the combination of a head adapted to support a razor blade, the under side of said head having a downwardly projecting threaded hub having a flat and smooth lower surface, a plate having a threaded shank projecting through the head and hub, a handle, the upper end portion of which is skeletonized into a yoke comprising a plurality of straps and a thimble threaded upon said hub, a nut journaled within the yoke between said straps and co-operating with said shank and plate and the lower hub surface to exert pressure upon the blade when the nut is rotated, by reaction against said lower surface.

2. In a safety razor, the combination with a handle, of a rigid head adapted to support a blade, said head having upturned marginal edges constituting a pair of straight smooth guard bars lying in a plane spaced outward from the plane of the main part of the head, slots being formed between the main portion of the head and the bars, the head having also along its upper side a narrow ridge midway between said guard bars and coextensive in length with the head and forming on its opposite sides channels to receive and hold shavings, an outer plate extending along the head and serving to bear upon and hold the blade against said ridge, and securing means for the plate extending through the head and co-operating with the handle, substantially as set forth.

In testimony whereof I affix my signature.

CHARLES M. SZIRMAY.
